UNITED STATES PATENT OFFICE.

JAMES P. FERRENBURG, OF OAK, NEBRASKA.

CHURN.

SPECIFICATION forming part of Letters Patent No. 367,284, dated July 26, 1887.

Application filed March 23, 1887. Serial No. 232,142. (No model.)

To all whom it may concern:

Be it known that I, JAMES P. FERRENBURG, a citizen of the United States, residing at Oak, in the county of Nuckolls and State of Nebraska, have invented certain new and useful Improvements in Churns; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in churns; and it has for its object to provide a device by means of which the churn-body may be firmly held when in use, and may be readily moved from place to place when so desired. It also aims to provide a device by which the churn-body may be easily removed from the inclosing and supporting frame for the purpose of removing the butter and cleaning the body. These objects I attain by the use of the device shown in the accompanying drawings, in which—

Figure 1 is a side elevation, Fig. 2 is a front elevation, and Fig. 3 is a plan view, of my improved device; and Fig. 4 is a detail view of the movable platform upon which the churn-body rests.

Referring to the drawings by letter, A designates the base of my improved churn-supporting frame, which is preferably rectangular in plan view and provided at its corners with the legs *a*, upon which it is supported when at rest. At or near the corners of the base I erect the posts or standards *B*, which are suitably braced by cross bars or beams *b*, as shown. The churn-body rests upon and is supported by the base, and the operating mechanism is mounted upon the posts or standards, as will be hereinafter more fully referred to. At a convenient distance above the base, at the front and rear of the frame upon the standards or posts *B*, I provide the rock-shafts *C*, journaled in bearings *c*, secured upon said posts. The ends of these rock-shafts are bent to form crank-arms *c'*, and pitmen *D* extend from these crank-arms down through the base *A*, and carry casters *d* at their lower ends beneath the base, and the rock-shaft is provided with a handle, *c''*, by means of which it can be

rotated to throw the crank-arms up or down, as may be desired. The pitmen *D* are made of such a length that when the crank-arms are raised the casters *d* will be off the floor and the frame will be resting on the legs *a*, as shown in Fig. 1; but when the crank-arms are thrown down the casters will rest upon the floor and the frame be elevated therefrom, as clearly shown in Fig. 2.

The base consists of the end sections, *E*, secured rigidly in place, and the movable or sliding section *E'*, which slides upon cleats *e*, formed on the inner edges of the rigid end sections, as will be readily understood upon reference to Fig. 4. The churn-body *F* rests upon this platform or sliding section and fits between the pins or stops *f* thereupon. The said sliding platform is provided with a caster, *G*, at its inner end, and its outer end is slotted near its opposite side edges, and the legs of a U-shaped bar, *H*, are pivoted within these slots and carry casters *h* at their lower ends. The shoulder of the U-shaped bar *H* is provided with a suitable handle, *h'*, by means of which the bar can be turned, so as to raise the casters from off the floor or lower them thereto, as may be desired. This U-shaped bar also serves as a convenient means for applying the force necessary to withdraw the platform from the base in order to remove the churn-body.

It will be readily understood that a frame constructed in the manner just described is adapted to receive and hold a churn-body of any description; but I have shown it in connection with a churn-body which is approximately cylindrical, and as provided with mechanism adapted to give the churn-dasher a vibratory motion. This mechanism I will now describe.

I is a drive-wheel, mounted on a shaft, *i*, which is journaled in suitable bearings on the top cross-bars of the frame, and is connected by a band or strap, *j*, to a pulley, *J*, mounted on one end of a shaft, *k*, which is also journaled at the top of the frame and carries the fly-wheel *K* on the end opposite the said pulley *J*. This fly-wheel *K* is provided with a pin or stud, *K'*, on its outer face, and a pitman, *L*, has one end connected to the pin or stud. The other end of this pitman is connected to a double-crank shaft, *M*, which is journaled upon the front of the frame near the upper ends

of the posts. This pitman may be connected directly to the crank-shaft M; but I prefer to connect it thereto by means of the rods *l*, which may be cast integral with said shaft, or keyed or otherwise rigidly secured thereto, as the dasher is thereby more rapidly vibrated, and the churning consequently more quickly accomplished.

N N are arms or rods, which have one end secured to the cranks *m* of the crank shaft M, and have their other ends engaging the cross-head *o* of the dasher O at its opposite ends, and n n are hooks provided on the opposite inner sides of the frame, at the top thereof, to support these rods N when they are disengaged from the cross-head and are not in use.

From the foregoing description, taken in connection with the drawings, it will be seen that when the drive-wheel is operated its motion will be communicated to the pulley J and fly-wheel K, and through the pitman L and double-crank shaft M to the dasher cross-head, the pitman and double-crank shaft converting the circular motion of the other parts into a vibratory or oscillating motion. The drive-wheel may be operated by hand by means of the handle P, or by means of the treadle Q at the base of the machine connected to the drive-wheel by a pitman, R.

It is thought that the uses and advantages 3c of my device will be readily understood from the drawings, taken in connection with the foregoing description, without a further detailed reference thereto.

Having described my invention, what I 35 claim, and desire to secure by Letters Patent, is—

1. A platform for supporting churns, comprising a pair of rigid sections and a movable section supported by said rigid sections, the 40 said movable section having a fixed caster at one end, and provided at its other end with a swinging frame carrying one or more casters, substantially as described and shown.

2. The combination of the base, posts erected 45 thereon, legs rigidly secured thereto, rock-shafts mounted on the posts, and pitmen depending from said rock-shafts and below the base, and carrying casters at their lower ends, substantially as and for the purposes set forth. 50

In testimony whereof I affix my signature in presence of two witnesses.

JAMES P. FERRENBURG.
